United States Patent Office

Des. 202,588
Patented Oct. 19, 1965

202,588

FRAME OF A SEWING MACHINE OR SIMILAR ARTICLE

Russell A. Fritts, Cranford, N.J., assignor to The Singer
Company, New York, N.Y., a corporation of New
Jersey

Filed Mar. 17, 1964, Ser. No. 79,051

Term of Patent 14 years

(Cl. D70—1)

Fig. 1

Fig. 2

Fig. 3

Fig. 4

Fig. 5

FIG. 1 is a front perspective view of a frame of a sewing machine showing my new design;

FIG. 2 is a rear elevational view thereof;

FIG. 3 is a top plan view;

FIG. 4 is an end view as seen from the left of FIG. 1; and

FIG. 5 is an end view seen from the right in FIG. 1. I claim:

The ornamental design for a frame of a sewing machine or similar article, substantially as shown.
